To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

The design consists of a series of ornamental panels formed of an ornament at the base of said panels, with ornamental scrolls and sprays of flowers and leaves extending from said ornaments and sprays of flowers and leaves springing from the top of said ornaments and forming the center of said ornamental panels, as shown in the accompanying drawing.

The border of the design is formed of simi-

lar ornamental panels with ornaments at the base and ornamental scrolls springing from said ornaments, with sprays of flowers and leaves springing from the top of said ornaments and forming the center of said panels, and festoons of flowers and leaves connecting said ornamental panels, as shown in the drawing. An ornamental band forms the bottom of the border, as shown, and separates the hanging from the border.

What I claim is—

In the design for wall paper, the border herein shown and described.

Witness my hand this 27th day of September, 1895.
